UNITED STATES PATENT OFFICE.

FRANK HALL GRANT, OF DETROIT, MICHIGAN.

SHINGLE.

1,076,111.

Specification of Letters Patent.

Patented Oct. 21, 1913.

Application filed April 17, 1913. Serial No. 761,781.

To all whom it may concern:

Be it known that I, FRANK HALL GRANT, a citizen of Canada, resident of the United States, residing at Detroit, in the county of 5 Wayne and State of Michigan, have invented certain new and useful Improvements in Shingles; and I do declare the following to be a full, clear, and exact description of the invention, such as will enable 10 others skilled in the art to which it appertains to make and use the same.

This invention relates to improvements in shingles and particularly to shingles formed of asphaltum paper or similar compositions.

One object of the invention is to provide a shingle of this character having its exposed end protected by a covering of thin sheet metal which imparts to the shingle all the 20 advantages of a metal shingle at a much less cost of production.

Another object is to protect the upper end of the shingle which underlies the crack between shingles in the row above, by an extension of said covering of sheet metal, and yet not materially increase the cost of the same.

Another object is to produce a shingle of this character which will be strong and 30 durable in construction, which will not rust, warp, split or leak, and which will be practically fire-proof and indestructible.

With these and other objects in view, the invention consists of certain novel features 35 of construction, and the combination and arrangement of parts as will be more fully described and claimed.

In the accompanying drawings: Figure 1 is a plan view of a portion of a roof illustrating the application of my improved 40 shingle; Fig. 2 is an enlarged top plan view of one of the shingles; Fig. 3 is a bottom plan view thereof; Fig. 4 is a central longitudinal section of the shingle taken on the 45 line 4—4 of Fig. 2; Fig. 5 is a cross sectional view of the shingle taken on the line 5—5 of Fig. 3.

My improved shingle comprises a body 1 which may be of any suitable size and shape 50 and constructed of any suitable material, the same being preferably constructed of asphaltum paper or similar composition. In the present instance the body 1 of the shingle is shown as of oblong shape and as having substantially the proportions of an ordi-

nary shingle. Arranged on the outer end of the shingle is a cap plate or covering 2 which may be formed of any suitable sheet metal, said covering being preferably formed of very thin sheet copper. The cap 50 2 covers the entire outer surface of the shingle for a distance somewhat greater than one-third the length of the shingle and the inner end of the cap or covering is tapered to a point which extends upwardly 65 for more than half the length of the shingle as shown at 3. The lower rectangular portion of the cap or covering has its sides and outer end turned in to form clenching flanges 4 which engage the adjacent edges 70 of the body of the shingle and are preferably pressed into the lower surface of the shingle, so that the outer surfaces of said flanges are flush with the surface of the under side of the shingle as clearly shown 75 in Figs. 4 and 5 of the drawing. The upper tapered end of the cap plate is also preferably pressed or embedded into the upper surface of the body of the shingle, so that the edges of said tapered upper end of 80 the covering are flush with the upper surface of the body of the shingle. The coverings 2 of the shingles when thus constructed are applied to the body of the shingle under heavy pressure which embeds the flanges 4 85 and upper edge of the covering into the composition forming the body of the shingle and thereby tightly clenches the covering in position on the shingle. The embedding of 90 the flanges 4 and edge of the upper end of 95 the covering in the body of the shingle permits the same to lie flat on a roof. In laying the shingles they are placed in courses with the shingles of one course breaking joint with those of the adjoining course in 100 the usual manner. The shingles are fastened to the roof by nails or tacks driven through the upper ends of the body of the shingle and into the sheathing boards of the roof as usual.

A shingle constructed in accordance with my invention will be a non-conductor of heat or cold and when properly laid will form an absolutely water tight covering for the roof which will not sweat or rust. The metal covering of the shingles will protect the latter from hail stones and heavy storms and the body of the shingle inclosed by the covering will act to deaden the sound caused by heavy storms or hail striking the roof. 110

Owing to the fact that the coverings are constructed from very thin metal the cost of a roof covered with my improved shingles will be considerably less than the usual metal roof.

The purpose of continuing the upper end of the metal covering into a point as shown at 3, is to cause it to underlie the crack between the shingles in the row next above so that water passing through this crack will fall upon the metal covering rather than upon the body of the shingle itself; and yet I preferably taper the upper edges of this extension to the point 3 so as to reduce as far as possible the amount of metal necessary for each shingle.

From the foregoing description taken in connection with the accompanying drawings, the construction and operation of the invention will be readily understood without requiring a more extended explanation.

Various changes in the form, proportion, and the minor details of construction may be resorted to without departing from the principle or sacrificing any of the advantages of the invention as claimed.

Having thus described my invention, what I claim is:

1. A shingle comprising a body, a cap formed of thin sheet metal and arranged over the lower exposed portion of said body and having its upper end tapered to a point and embedded in the upper surface of said body, and clenching flanges formed on the side and lower end edges of the cap and embedded in the lower surface of the body of the shingle.

2. A shingle comprising a body formed of fire- and water-proof material, and a metal cap overlying the lower end of said body and its sides and end, with the upper end of said cap tapered to a point and overlying the central portion of the body, for the purpose set forth.

In testimony whereof I have hereunto set my hand in presence of two subscribing witnesses.

FRANK HALL GRANT.
